UNITED STATES PATENT OFFICE.

JOHN F. O'CONNOR, OF CHICAGO, ILLINOIS, ASSIGNEE TO WILLIAM H. MINER, OF CHAZY, NEW YORK.

DRAFT-YOKE FOR RAILWAY-CAR DRAFT-RIGGING.

Specification of Letters Patent. Patented Dec. 3, 1913.

1,286,732.

Application filed July 31, 1916. Serial No. 112,346.

To all whom it may concern:

Be it known that I, JOHN F. O'CONNOR, a citizen of the United States, residing at Chicago, in the county of Cook and State 5 of Illinois, have invented a certain new and useful Improvement in Draft-Yokes for Railway-Car Draft-Rigging, of which the following is a full, clear, concise, and exact description, reference being had to the accompanying drawings, forming a part of 10 this specification.

My invention relates to improvements in draft yokes for railway car draft rigging.

The object of my invention is to provide 15 an efficient draft yoke which may be readily connected to, and disconnected from, a draw bar.

In the drawings forming a part of this specification, Figure 1 is a side elevation, 20 partly in vertical longitudinal section of a draft yoke embodying my invention. Fig. 2 is a horizontal section taken on line 2—2 of Fig. 1. Fig. 3 is a front end view. Fig. 4 is a perspective view of the latch and 25 Fig. 5 is a vertical longitudinal section of the lower forward portion of a yoke, illustrating a modified form of latch and latch connection.

Referring to the drawings, the numeral 6 30 indicates the upper limb, 7 the lower limb and 8 the rear connecting member of the draft yoke. At its forward end the yoke is provided with a hollow head to receive the draw bar 9, the said draw bar being provided with the usual upper and lower shoulders 10 and 11, respectively. The head is provided at its upper portion with an inverted gib 12, adapted to engage the upper draw bar shoulder 10, its lower portion being closed by the swinging latch 13 which 40 is mounted between the side plates 14, 14 of the yoke head. The latch 13 comprises a member 15, provided at its forward end with a gib 16, adapted to engage the lower draw bar shoulder 11, and also provided at its rear 45 end with a hinged, or other swinging connection, to the lower yoke limb, as the hinge butt and pintle structure indicated at the numeral 17 in the drawing. The said latch 50 is also provided with an arm 18 adapted for passage through the slot 19 provided in the transverse connecting member 20 of the yoke

head. The said arm 18 is provided with a perforation 21, registering with perforations 22—22 in the transverse member 20 for the passage of the bolt 23, which is adapted to hold the arm in a fixed position. The said arm is also provided with a perforation 24, adapted for the passage of a tool, such as the bar 25 indicated by the dotted lines in Fig. 1 of the drawing, for an easy manipulation of the latch. It is obvious that other tools, such as wrenches, may be likewise employed.

In assembling the draw bar and yoke, the latch is placed in a position permitting the lower face of the draw bar to be mounted upon the upper angular edge 26 of the latch, which edge, when the latch is in unlocked position, will be substantially parallel with the limbs of the yoke. The draw bar is then moved rearwardly a sufficient distance to permit the shoulders 10 and 11 thereof to be rearward of the gib 12, and by the upward forcing of the latch, the draw bar is lifted into its position, the upper shoulder 10 engaging the gib 12, and the lower shoulder 11 engaging the gib 16 upon the latch. The said latch is then secured in its locked position by the insertion of the bolt 23.

To disassemble the draw bar and yoke, the fastening for the latch, such as the bolt 23, is removed, the latch descending until its lower face 30 is stopped against the transverse member 20 of the yoke head, and the draw bar then may be withdrawn forwardly, the lower face of its butt sliding for the length of the angular face 26 of the latch thereon.

In the modification illustrated in Fig. 5, the numeral 40 indicates the draw bar, 41 the lower shoulder thereof, 42 the latch provided with the shoulder 43 to engage the shoulder 41 of the draw bar 40, 44 the arm 45 upon the latch, 46 the lower transverse connecting member in the yoke head, one of the said plates being shown at 46, all of these parts being the same as those shown in the preferred form of structure illustrated in Figs. 1 to 4, inclusive, of the drawing, with the exception of the means for swingingly connecting the latch to the yoke, which comprise a hook 47 provided on the rear end

of the latch, adapted to engage an opposed hook 48 formed upon the lower limb 49 of the yoke.

I claim:

5. 1. In a draft yoke for railway car draft rigging, a gib adapted to engage a shoulder upon a draw bar, a swinging latch secured thereto and having a gib to engage another shoulder on a draw bar, the said latch having an arm to receive a tool, whereby the latch may be swung into locking, or unlatching, position in reference to the draw bar.
10. 2. In a draft yoke for railway car draft rigging, upper and lower limbs, lateral plates connecting the same and forming a yoke head to receive a shouldered draw bar, a latch, the upper limb being provided with a gib to engage one shoulder of a draw bar,
15. 20. the latch having a gib to engage another shoulder of a draw bar, the latch being swingingly connected to the yoke, the yoke head having a lower transverse member, the

latch having an arm associated with said transverse member and being provided with 25 means for securing said arm in a fixed position in relation to said transverse member.

3. A yoke for draft gears comprising top and bottom members connected at their rear ends, side plates integral with said top and 30 bottom members and extending below the latter, a web connecting the extensions of said side plates, a lug on said top member, means supported between said side plates, having a corresponding lug, an abutment to receive 35 stresses transferred through said means, and an opening in said web to permit manipulation of said means.

In witness that I claim the foregoing I have hereunto subscribed my name this 28th 40 day of July, 1916.

JOHN F. O'CONNOR.
